(57) **CLAIM**

The ornamental design for a toy, as shown and described.

DESCRIPTION

FIG. 1 is a perspective view of the toy embodying the design.

FIG. 2 is a side elevation of the toy of FIG. 1.

FIG. 3 is a top plan view of the toy of FIG. 1.

FIG. 4 is a side elevation of an ear of the toy of FIG. 1.

FIG. 5 is a side elevation of an ear of the toy of FIG. 1 taken opposite FIG. 4.

FIG. 6 is a top plan view of the ears of the toy of FIG. 1.

FIG. 7 is a front elevation of the ears of the toy of FIG. 1; and,

FIG. 8 is a rear elevation of the ears of the toy of FIG. 1.

The body and head of the toy shown in phantom lines is disclaimed and does not form part of the design.
